(57) **CLAIM**

I claim the ornamental design for a holder for multiple beverage containers, as shown and described.

DESCRIPTION

FIG. 1 is an upper perspective view of the holder for multiple beverage containers showing my design.

FIG. 2 is a front view thereof, a back view being an identical image thereof;

FIG. 3 is a side view thereof, an opposite side view being an identical image thereof;

FIG. 4 is a top plan view thereof; and,

FIG. 5 is a bottom view thereof.
